(57) **CLAIM**

The ornamental design for a jaw crusher front frame end, as shown and described.

DESCRIPTION

FIG. 1 is a perspective view from above of the front of a jaw crusher front frame end according to the present design.

FIG. 2 is a perspective view from below of the back of the jaw crusher front frame end of FIG. 1.

FIG. 3 is a front view of the jaw crusher front frame end of FIG. 1.

FIG. 4 is a rear view of the jaw crusher front frame end of FIG. 1.

FIG. 5 is one side view of the jaw crusher front frame end of FIG. 1, with the other side being a mirror image thereof.

FIG. 6 is a top view of the jaw crusher front frame end of FIG. 1; and,

FIG. 7 is a bottom view of the jaw crusher front frame end of FIG. 1.

1 Claim, 7 Drawing Sheets
